Patented Jan. 15, 1929.

UNITED STATES PATENT OFFICE.

HENRY MOECKER, JR., OF FLOSSMOOR, AND THEODORE THOMPSON AND OTTO HAMMERMEISTER, OF HARVEY, ILLINOIS, ASSIGNEES TO AMERICAN STOVE COMPANY, OF ST. LOUIS, MISSOURI, A CORPORATION OF NEW JERSEY.

RANGE.

Application filed February 12, 1927. Serial No. 167,735.

This invention relates to improvements in ranges and is constructed from sheet steel or iron and is more particularly intended for use in a gas range.

5 One feature of the present improvement is the construction of the frame that encloses the oven and broiler doors and the door itself for the purpose of making an efficient smooth and sanitary construction.

10 Another feature of the invention is combining with the frame a journal block and with the door a hinge block cooperating with the journal block, both the said members being enclosed within the frame and the

15 door. A further feature of the present invention is to so construct the journal block that it is adapted to receive and support a cross shield for the purpose of protecting the 20 adjacent parts from the excessive heat of the oven or the broiler.

Another feature of the present improvement is to so construct the journal blocks that the cross shield is supported by the 25 journal blocks and held against endwise movement without the use of any bolts or screws.

The said improvement also relates to the form of the shield whereby the outer member of the shield is supported by the journal 30 blocks and the inner member is supported by the outer member, the two members adapted to receive an asbestos or other non-inflammable packing, whereby the said device efficiently acts as a means of protection to itself and to the adjacent parts from the 35 heat of the burners.

Another feature of the present improvement is combining with the journal blocks an inner and outer part shield, the outer 40 part shield having its upper and lower edges turned inwardly, downwardly and upwardly respectively, and the inner part having its edges shaped to interlock with the said edges of the outer part, the whole device constructed to cooperate with and be permanently supported by the said journal blocks.

A further feature of the present invention pertains to the construction and cooperation of the journal blocks, the hinge 50 blocks and a two-part rod, the outer end of the two parts passing through the hinge blocks and into the journal blocks, and a coil spring surrounding the said two parts

of the rod, the two parts of the rod being 55 supported in a manner whereby the spring acts as a means of holding the said doors closed.

Another improvement of the present invention pertains to the construction of the 60 hinge blocks whereby they are adapted to receive the ends of the supports or catches for limiting the movement of the doors to horizontal positions, the holders or catches having their inner ends constructed to co- 65 operate with the frame or the journal blocks to support the doors in their horizontal positions.

Other features of the invention will appear from the following description. 70

Referring to the drawings:

Figure 1 is an end view of my improved range showing a front view of the said frame and oven and broiler doors.

Figure 2 is an inside front view showing 75 the hinge blocks, the journal blocks, the rod and the spring.

Figure 3 is a vertical sectional view through the frame showing the shield members, one of the doors and its cooperating 80 parts.

Figure 4 is a cross sectional view through one side of the frame showing the hinge 85 block, the journal block, and one end of the hinge rod.

Figure 5 is a view partly in vertical section, through the hinge portion of the door and showing the journal block, the hinge block and the manner of supporting the inner shield member by the journal block. 90

Figure 6 is a vertical sectional view at right angles to Figure 5, taken through one edge of the door on dotted line 6-6 of Figure 1, showing the shield members in vertical section, the hinge block and its 95 cooperating holder, said door being shown in a horizontal position.

Figure 7 is a front view of one edge of the frame for the doors.

Figure 8 is a vertical sectional view 100 through the center of the said frame, illustrating in section the cross parts thereof.

Figure 9 is a perspective view of one edge of the outer shield member.

Figure 10 is an inside front view of one 105 end of the outer shield member.

Figure 11 is a perspective view in section of the inner shield member.

Figure 12 is a front view of one edge of one of the doors.

Figure 13 is a vertical edge view of one of the doors.

5 Figure 14 is a vertical inner view of one edge of the door lining.

Figure 15 is a vertical edge view of the said lining.

10 Figure 16 is a detached perspective view of the latch or holder with its combined holding member shown in detached relation.

15 Figure 17 is a perspective view of the hinge rod, the same being partly shown for the purpose of illustrating the reduced end of one part of the rod and the other end adapted to receive the reduced end.

In Figure 1 I have shown a front view of the complete range, the left hand side 20 1 being the open burner part of the range, while the other side 2 is the oven and broiler part of the range. In this figure, 3 is the oven door and 4 the broiler door. In the form of the invention here illustrated, the 25 frame 5 is composed of a single piece. By this it is meant that its upper end 6, its lower end 7 and its cross member 8 are of one piece stamped from a single sheet of metal. This frame is made of an improved 30 cross sectional shape, and it is made of such form that it is very efficient, smooth and sanitary in its formation.

It is well known that ranges are great 35 collectors of dust and dirt, and one feature of this present invention is to so form this frame in cross section combined with the cross section of the said doors whereby the same can be readily kept free from the accumulation of dirt, germs, and the like.

40 By reference to Figure 8 the contour of the frame is shown, and Figure 7 shows the same from the front. From Figure 8 it will be observed that in general form the frame 8 is U-shaped, it having outwardly bulged 45 portions 9 located just above the cross member 8, and the outline of this bulged portion is such as to make it so that it can be readily cleaned. By reference to the same figure, it will be observed that the upper 50 end of the frame is bent inward in symmetrical form at 10, then downward as at 11 and then a short inward bend 12. These bends are all made so that it can be readily cleaned. This construction further produces an outward bent portion 13. At its 55 lower end this portion is not so decided since it extends downward as shown at 14 and is provided with suitable hole or holes 15 for connecting the said frame to the range 60 structure 17.

The frame 5 is also provided with an outward bulge 18 located at its outer side just above its portion 13. The outwardly bulged portion 18 agrees with the outwardly 65 bulged part 9. Attention is directed to the

fact that the cross member 8 has its upper edge 19 turned inward and its lower portion turned inward corresponding to that described at the upper part of Figure 8. Therefore reference letters and other description of this part of the structure is wholly unnecessary.

70 By reference to Figure 6, the cross sectional structure of the door 3 is clearly shown. It will be observed that its free edge 20 is bent inward, thus making a deep structure, the said inner end at its lower corners 21 being bulged outward to its edge, as shown at 21, Figure 1, for the purpose of receiving the hinge block to be described 80 presently.

85 Referring particularly to Figure 5, the construction and operation of the journal blocks will be described. These blocks in general outline are substantially L-shaped, the lower leg 22 being substantially short, while the upper leg 23 is elongated upwardly. By reference to Figure 4 it will be observed that this journal block in cross section is substantially the same as the cross 90 section of the frame and that it is embraced by the cross section of the frame whereby it serves among other things, as a brace for the frame. Its outer edge 24 is provided with a bolt opening through which a bolt 95 25 passes for the purpose of holding the upper end thereof in position, the lower end being held by a suitable bolt 26 that passes through it to the frame. These two bolts 25 and 26 serve to permanently hold the 100 journal block to the frame. The lower end 22 of the journal block is provided with an outwardly bulged portion 27, its inner end having lips 28 and 29, located out of line and between these lips the end of the inner 105 shield member 30 is passed. The above described construction applies to both of the journal blocks, which makes it unnecessary to refer to the other journal blocks. It will be observed, therefore, that the inner member 30 of the shield is held between the ends of the bulged portions 27 and the said lips, therefore serving to hold it permanently in position. In assembling these members, one 110 of the journal blocks would be placed in position and then the inner shield member and the other journal blocks made to engage the other end of the inner shield member 30, thus locking it in its position.

115 From Figure 9 it will be observed that the outer shield member has its portion 31 bulged whereby it fits the bulged portion 27 and fits between the lugs 28 and 29. This shield member also is bent downward at 32 intermediate its upper and lower edges and then inward as at 33 and its inner lower extremity provided with an upwardly bent U-shaped portion 34. Attention is also directed to the fact that the upper edge is likewise bent into a U-shape 35 that extends 125 130

downwardly. The ends 36 of this shield member are extended for the purpose of fitting on the inwardly extending bulge 27 and for the purpose of making a closed structure with the door lining 37, which fits against the inner edge of the shield member throughout its length. This lining 37 has its edge bent inward as shown at 38 and it fits within the edge 20 of the door 3. The inner shield member 39 has the peculiar form clearly shown in Figures 6 and 11. It will be observed that its inner edge has a double upward bend as illustrated at 40, and its lower edge a similar bend 41, and that the upper bend is of larger dimensions than the lower bend. The upper edge 40 of the member 39 fits within the U-shaped bend 35 of the upper edge of the outer shield and its lower edge 41 fits within the lower U-shaped bend 34 of the said outer shield member. Consequently this member 39 is likewise held in position by having the ends of the upper edge 40 strike the end of the bulged portion 27 of the hinge block, the said member 39 being placed in position on the outer member before placing on the last journal block. From the foregoing description it will be seen that there is a space between the inner and outer shield members, and a part of this space is filled in with asbestos 42 or any like material. It will be observed that this asbestos stands in a vertical line and it serves to protect the hinge members from the heat and flame of the burner in the broiler part of the range, as well as to protect the outer shield member from said heat.

Attention is directed to the construction of the upper end of the inner shield member 39 by having its horizontal portion 43 extending beyond the lip of the U-shaped bend 35 of the inner shield member 31. This shoulder 43 forms a support for the floor 44 of the oven. In the construction here shown, the oven floor 44 has its edge 45 turned downward and resting on the shoulder 43. Therefore this shield member is so constructed that in addition to acting as a shield, it also acts as a support for the front end of the floor of the oven.

By reference to same figure of the drawing (Figure 6), the said construction of the lining 37 and the means by which the lining is supported, are shown. This consists essentially in a member 46 that has its upper end 47 bent laterally and attached to the lining 37 by suitable bolts 48. The lower end of this member 46 is bent inwardly as shown at 49 and engages the inner side of the door 3. This door is provided with suitable outwardly bent portions 50 on which the stems 51 of a handle 52 engage, and the end 49 is also bent to fit within this bend 50 and screws 53 pass through the bent portion 49 and the wall

of the door and into the stem 51. In this manner the upper end of the lining and the handle are attached to the door 3. The inner or lower end of the lining 37 rests upon the hinge block 54 and is attached to the hinge block by suitable screws 55. It will be understood, of course, that there are two bearing blocks 23 for each door, same being the upward extensions of the journal blocks, one located to cooperate with the hinge block attached to the lower portion of the doors in a manner to be presently explained. Therefore it is unnecessary to describe the other block as it is constructed exactly like the one already described.

In Figures 2, 4 and 6 the hinge blocks are particularly shown. These hinge blocks 54 consist essentially of L-shaped members which comprise vertical leg portions 56 and horizontal leg portions 57. Suitable attaching bolts 58 pass through the upper ends of the leg portions 56 and the door and the lower portion of these hinge blocks is attached to the door by suitable connecting bolts 59. In this manner the hinge blocks are secured to the door. It will be noted that the hinge blocks are attached to the lower outer corners of the door.

For the purpose of forming a bearing on which the door turns, a two-part rod is provided. One part 60 passes through the lower leg 57 and has its end fastened to the journal block 23 by a screw 61 passing through the journal block and engaging the extremity of the part 60. The other part 62 of the bearing rod passes through the leg 57 and is fastened thereto by a screw 63 which passes through the said leg portion and engages the part 62. Therefore the parts 60 and 62 are relatively movable when the door is moved on its hinge. This is accomplished by providing the part 60 with a reduced projecting end 64 that loosely enters a longitudinal opening 65 formed in the inner end of the part 62 of the hinge rod. Surrounding the inner adjoining ends of the two parts 60 and 62 is a suitable spiral spring 66, the respective ends 67 and 68 of the spring being attached to the respective ends of the parts 60 and 62 of the rod by suitable screws 69.

It will be understood from the foregoing explanation that the outer end of the part 60 of the hinge rod is made fast to the journal block 23 or may be attached in any manner to the frame of the door, the lower leg portion 57 turning freely on the part 60 of the rod, while the rod 62 is made fast to its hinge block 54 and has its extremity 70 resting loosely in a suitable opening formed in the journal block whereby the part 62 of the rod turns with the door while the part 60 of the door is stationary. By this means tension can be readily placed on the spring 130

by inserting a suitable tool or wire in one of the openings 71 and turning the part 62 until the proper tension is obtained, when the screw 63 is turned in, and the parts are 5 ready to operate. In this manner the coil spring is made to act as means for closing and holding closed the doors as will be readily understood.

It is essential that some means be provided for limiting the downward movement of the door and holding it in a horizontal position. The means are shown consisting preferably of a flat metallic member 72, the end 73 thereof being pivoted near the extremity of the vertical leg 56 of the hinge blocks. This is accomplished by passing a suitable screw or other bearing 74 through the leg portion 56 and having its end extended and passing through the extremity 15 of the said member 72. For the purpose of accommodating the member 72, the hinge block has its edge cut out as shown at 75 to accommodate the end of the member 72, thereby the end 72 is held between the hinge 20 block and the inner side of the bend 20 of the said door. By turning the member 74 and taking it out of position, the lower extremity of the member 73 will be released. Suitable openings 76 are formed in the side 25 flanges of the frame 5, and through these openings the upper ends of the member 72 loosely pass. Attached to the upper end of the member 72 is a suitable block 77 by means of a screw 78. The inner end of this 30 block or stop member 77 is formed at an incline as shown at 79. This incline strikes the journal block 23 at substantially the point 80. Of course it will be understood that the walls of the openings 76 serve to 35 hold the member 72 against upward movement and therefore lock or hold the door in its lowermost position. The block 77 in addition, serves as a weight to hold the inner end of the members 72 to their proper positions and is in a sense a balance weight for the free end of the member 72. For the 40 purpose of holding the doors in a closed position, the members 72 are provided with notches 81 which form shoulders 82 that engage the journal blocks substantially at the point 80. When the door is closed, this shoulder 82 drops behind the part 80 of the journal blocks so that a sudden pull is necessary to cause the members 72 to be free of 45 said engagement, and after this free movement is accomplished, then the door will readily open. In this manner locks or catches for holding the doors closed is provided and the other ends of the same members 50 serve as means to limit the distance the doors will open. The spring of course, will be adjusted to a point that when the door has reached a horizontal position, the weight will be sufficient to hold them in that position. Since they are to be closed, a slight 55

upward pull will carry the door past a point when the springs will close the doors if they should be released.

At this point attention is called to the fact that the lining 37 of the door and the floor 70 44 of the oven are exactly in a horizontal line, and that this enables the pans and other things to be moved back and forth over the floor to the door and from the door to the floor of the oven without lifting them. This 75 will be found by users to be extremely convenient.

For the purpose of enabling the oven or the broiler doors to be removed from the front without the necessity of first removing 80 the lining of the oven or the broiler or disturbing any bolts of the range proper, the two-part hinge rod may be moved inward or collapsed until the extremities of the said two-part rod are released from the journal 85 blocks, when the door can be readily removed. In order to accomplish this it is only necessary to remove the lining of the door. After this the screws 61 and 63 are loosened and one end of the spring 66 removed to release one end of the spring. This having been done by moving the inner ends 90 of the two rods together, their extremities are released from the journal blocks as will be readily understood.

While the present improvement has been described in considerable detail, we do not wish to limit the scope of the claims thereby, but wish all the claims construed as broadly as possible in view of the state of the art.

Having thus described our invention, what we desire to claim and secure by Letters Patent of the United States is:

1. In a range, the combination of an oven door frame and a door therefor, a hinge for the door, said hinge comprising bearing blocks connected with the inner side of the frame and hinge blocks attached to the inner side of said door, and a bearing rod passing through the said hinge blocks into the said bearing blocks.

2. The combination in a range of a door frame, a door fitting therein, journal blocks carried at the inner side of said frame, hinge blocks carried at the inner side of the said door, and hinge rods connecting the said journal blocks and hinge blocks for the purpose specified.

3. In a range having a door frame, a door in said frame, the frame carrying journal blocks, the said door carrying hinge blocks, said blocks being operatively connected by laterally movable hinge rods, said doors being detachable by moving the hinge rods endwise.

4. In a range, a door frame and a door fitting within said frame, journal blocks attached to the inner side of said frame, hinge blocks connected to the inner side of said door, and a two-part hinge rod passing

- through the hinge blocks into the journal blocks, said door being removable by sliding the two hinge rods toward each other to release their extremities from the journal blocks.
5. A range having a door frame, a door fitting within said frame, journal blocks secured to the door frame, hinge blocks attached to the inner side of the said door, a two-part hinge rod passing through the hinge blocks into the journal blocks, means for securing one part of the rod to one of the hinge blocks, and means for securing the other rod to one of the journal blocks, and a spring connecting the rods for the purpose of closing the said door.
6. A gas range comprising a door frame, a door within said frame, journal blocks attached to the inner sides of said frame, hinge blocks attached to the inner side of said door, a two-part hinge rod passing through the hinge blocks into the journal blocks, the inner ends of the said rod being capable of telescoping, means for securing one rod to one of the hinge blocks and the other rod to one of the journal blocks, and a coil spring surrounding the hinge rod having its ends connected respectively to the two parts of the said hinge rod for the purpose specified.
7. A gas range having a door frame, having its edges turned inward, a door fitting within said frame, journal blocks located between the two inturned edges, means for connecting the journal blocks to the frame, a door fitting within the frame having L-shaped hinge blocks connected therewith, the lower legs of the L extending inward from opposite sides of the door, a two-part hinge rod passing entirely through the lower leg of the said hinge blocks and into the journal blocks, means for fastening one part of the rod to one of the hinge blocks and means for connecting the end of the other rod to the journal blocks for the purpose specified.
8. A range having a door frame, a door fitting therein and having its lower end pivotally connected with the frame, and means for limiting the opening movement of the door, said means comprising a member having its lower extremity pivotally connected with the door and its upper end passing through an opening in the said frame, the said member having a notch in its un-
- derside adjacent its pivoted end, whereby when the door is closed, the wall of the notch acts to hold the said door in a closed position.
9. A range comprising an oven and a broiler, said range having an oven door frame provided with two door openings, a door located at its lower edge on the frame intermediate its ends, and a shield member located below the oven door and between the source of heat of the broiler and the said hinge, said shield having its upper and lower edges bent substantially U-shaped and an inner shield member interlocking with and held by said edges for the purpose specified.
10. A range comprising a door frame having two door openings, journal blocks attached to the said frame and having their lower portions extending inwardly, of a shield member located between the ends of the said blocks and held thereby in its position for the purpose specified.
11. A range having a door frame, a bearing block attached to the frame, said door hinged to the bearing block, the bearing block extending upwardly and having a cut-away portion, hinge blocks connected with the door having upwardly extending portions and a member pivotally connected with the hinge block and its opposite end provided with a stop adapted to engage the cut-away portion of the bearing block for limiting the opening movement of the said door.
12. A range comprising a door frame having bearing blocks attached thereto with upwardly extending portions, hinge blocks connected with the door and having upwardly extending portions, a link for limiting the opening movement of the door having one end hinged to the hinge block between it and the edge of the door, and the upwardly extending portion of the bearing block having a shoulder, and the link having a stop adapted to engage the said shoulder when the door is opened.

In testimony whereof, we hereunto affix our signatures.

HENRY MOECKER, JR.
THEODORE THOMPSON.
OTTO HAMMERMEISTER.
